UNITED STATES PATENT OFFICE.

HAROLD E. SHAW, OF MAYWOOD, ILLINOIS.

ROTARY CAN-TIPPING MACHINE.

1,156,634.

Specification of Letters Patent. Patented Oct. 12, 1915.

Application filed January 7, 1915. Serial No. 964.

To all whom it may concern:

Be it known that I, HAROLD E. SHAW, a citizen of the United States, residing at Maywood, in the county of Cook and State 5 of Illinois, have invented certain new and useful Improvements in Rotary Can-Tipping Machines, of which the following is a specification.

My invention relates to improvements in 10 rotary can tipping machines, or more plainly speaking to a machine for sealing the center vent opening in cans.

One object of my invention is the provision of a machine which will feed the cans, 15 apply the solder, effect the soldering and deliver the cans with the vent opening sealed, the operation being continuous, efficient and rapid, thus insuring a great saving of time and expense and the highest 20 degree of efficiency.

Another object of my invention is the provision of a machine of the character and for the purpose stated, which will insure 25 the melting and application of the solder in a smooth and even manner and which will be capable of adjustment to guide and accommodate cans of varying sizes.

Another object of my invention is the provision of a machine which will insure 30 a saving of time and a high degree of efficiency and which will be small and compact in size, simple, strong and durable in construction and inexpensive; to possess the requisites, to insure a thoroughly reliable 35 and practical improvement.

With these objects in view my invention consists of a machine for sealing center vents in cans, embodying novel features of construction and combination of parts for 40 service, substantially as disclosed herein.

In order that the detailed construction and operation of my machine may be fully understood and its many advantages and features of merit be appreciated, I have 45 shown in the accompanying drawings a machine constructed in accordance with my invention.

Figure 1 represents a top plan view of the complete machine. Fig. 2 represents a side 50 elevation thereof. Fig. 3 represents one of the plates which are secured to the rotary

carrier or star wheel for varying the adjustment of said wheel to suit the can, and Fig. 4 represents a detail view of an adjustable means to be applied to the track at the exit 55 of the can.

Referring by numerals to the drawings in which similar numerals denote like parts in the four views, the numeral 1 designates the bed or base, from which depend the pair 60 of lugs 2, for securing the base to a suitable support, the standards being connected by the top bar or plate 3, and at one side of the bed travels the endless belt or apron 4. The said belt is of any desired construction and is suitably driven and in proper relation thereto, and to the machine is mounted supports 5, to which are secured curved guides 6, and in parallel relation to said pair of guides 6 are supported by posts 70 7, and threaded rods 8, the guides 9. This construction provides with reference or relation to the belt an entrance guide and an exit or discharge guide for the cans 10, whose central vent opening 11, is to be supplied with the desired amount of solder, the said guides being thus disposed in proper position to the can guiding rail 12, retained by the series of adjustable rods 13, and posts 14, in which said rods 13 are mounted. 80 It will thus be seen that the guiding rail 12 and the entrance and exit guides 6 and 9, are arranged in such manner with reference to the endless belt, that the can is carried by said belt and received and conducted by 85 the entrance guide upon the bed and is delivered or discharged upon said belt by the exit guides after being operated upon by mechanism which I will now describe.

In the bed of the machine is an opening 90 15, forming the bearing for the vertical shaft 16, mounted for rotation upon the threaded spindle 17, and driven by suitable power, and upon the shaft 16, is secured by means of the sleeve 18, the rotary carrier or 95 star wheel 19. This wheel is of novel and peculiar construction having the series of can receiving pockets 20, which act in conjunction with the guiding rail 12 and the guides 6, and 9, to take the can from the 100 belt at its entrance 21, carry it around in contact with the rail 12, and when soldered

discharge the can at the exit 22, as indicated by the arrows. To adjust the pockets according to the size of the cans the strips 23 are provided, which are secured to the wheel 5 by fastenings 24. From this construction it will be seen that the cans are fed from the belt to the bed of the machine and are guided by the rail and guides, and carried continuously from their entrance to exit by the 10 rotary wheel, and that the cans are revolved by contact with the pockets of the wheel and guide rail, and upon the shaft 16, at its upper end, is secured the gas chamber 25, having the feed pipe 26, rotatably mounted by 15 means of the cap 27 in the cross-bar or plate 3.

The gas chamber is in communication with the supply, and has mounted therein the series of branch pipes 28, having regulating cocks 29, the branch pipes communicating by means of the pivoted nipples 30, with the steel or implement feeding pipes 31, from which depend the soldering steels 32. It will thus be seen that the gas chamber 25 with the series of connections revolve and that the said connections permit a raising and lowering of the steels and that the steels are disposed over the closure of the pockets to bring them directly above the 30 center vent opening of the cans.

To the steels are secured the studs 33, upon which are mounted the rollers 34, which travel upon the track 35, supported by the pair of yokes 36, and the portion 38 of the track is in a higher plane than the portion 37, the purpose of which is to hold the steels in elevated position while on the raised portion 38, thus providing the cans free entrance to, and exit from the machine 40 and at the same time allowing the steels to fall when entering the depressed portion 37 and this permits the steels to contact with the solder thereon and effect the sealing of the vent opening while the steel is traveling 45 in lowered position upon the depressed portion of the track.

It will be seen that the can is directed by the guides into one of the pockets of the wheel and revolved with the steel in elevated 50 position above the center opening of the can and in this position as soon as the roll enters upon the depressed portion of the track, the steel upon which it is mounted drops upon the opening of the can, and the vent 55 opening is sealed by the solder.

The device shown in Fig. 4, is attached to the track at the end of depressed portion 37 and consists of a plate 39, having slotted ends 40, adjustable on pins 41, to regulate 60 the time the steel shall travel on the track in finishing the soldering.

From the foregoing description taken in connection with the drawings the operation and advantages of my machine will be read-

ily understood and it will be observed that 65 the cans are fed from the belt to the bed, and are received and carried by the wheel, and that the steels melt the solder while the cans are revolved, and that when the sealing is completed the cans are directed to the 70 belt and carried away in finished condition, thus saving a great amount of time and expense, and performing the service in a thoroughly efficient manner.

It will be noted that the cans are operated 75 upon successively and automatically; that each can receives the same treatment; that the machine is small and compact in size, while of large handling capacity; is easy to control and inexpensive to maintain; and that generally speaking is thoroughly efficient and practical.

I claim:

1. In a machine of the character described, the combination with an endless can conveyer, of a bed arranged adjacent thereto, curved guides leading from the endless conveyer to guide the cans to and from said bed, a rotary can carrier for receiving the cans from said conveyer, and means rotating with said can carrier to solder the center opening in said cans and means for determining the length of time said soldering means operate upon the cans.

2. In a machine of the character described, 95 the combination with an endless can conveyer, of a bed arranged adjacent thereto, curved guides leading from the endless conveyer to guide the cans to and from said bed, guides for the cans in communication with 100 said conveyer, a rotary can carrier for receiving the cans from said conveyer, and means rotating with said can carrier to solder the center opening in said cans and means for determining the length of time 105 said soldering means operate upon the cans.

3. In a machine of the character described, the combination with an endless can conveyer, of a bed arranged adjacent thereto, curved guides leading from the endless conveyer to guide the cans to and from said bed, a rotary can carrier for receiving the cans from said conveyer, adjusting means carried by the said can carrier, and means 110 rotating with said can carrier to solder the center opening in said cans and means for determining the length of time said soldering means operate upon the cans.

4. In a machine of the character described, the combination with an endless can conveyer, of a bed arranged adjacent thereto, curved guides leading from the endless conveyer to guide the cans to and from said bed, a rotary can carrier for receiving the cans from said conveyer, and means rotating 120 with said can carrier to solder the center opening in said cans, said means consisting of a gas supply chamber, and a series of sol-

dering implements in communication with said chamber and means operating upon the soldering implements to determine the length of time the implements shall be applied in finishing the soldering.

5. In a machine of the character described, the combination with a can conveyer, curved guides leading from the endless conveyer to guide the cans to and from said bed, a bed to receive the cans from said conveyer, a rotary can carrier, a series of rotary soldering implements disposed above the center of the cans, and a track upon which the said implements travel and are guided and means operating upon the soldering implements to determine the length of time the implements shall be applied in finishing the soldering.

6. In a machine of the character described, the combination with a can conveyer, a bed to receive the cans from said conveyer, curved guides leading from the endless conveyer to guide the cans to and from said bed, a rotary can carrier, a series of rotary soldering implements disposed above the center of the cans and a track upon which the said implements travel and are guided, said track having a raised portion to hold the implements in elevated position and a depressed portion to allow said implements to descend upon and seal the cans and means operating upon the soldering implements to determine the length of time the implements shall be applied in finishing the soldering.

35 7. In a machine of the character described, the combination with an endless can conveyer, a bed to receive the cans, guides to direct and discharge the cans, a rail to retain and guide the cans, a rotary wheel having pockets to receive said cans, a track having a raised and depressed portion, a gas supply chamber, a series of soldering implements pivotally connected with the gas chamber, and rollers carried by said implements and traveling upon said track to raise and lower the implements and means operating upon the soldering implements to determine the length of time the implements shall be applied in finishing the soldering.

50 8. In a machine of the character described, the combination with a supporting structure, a rotary can carrier mounted therein, a rotary soldering mechanism above said carrier and means for throwing the soldering mechanism into and out of operation and means operating upon the soldering implements to determine the length of time the implements shall be applied in finishing the soldering.

60 9. In a machine of the character described, the combination with a can conveyer, a bed to receive said cans, a rotary shaft mounted in said bed, a can carrier and gas supply mechanism carried by said shaft, a series of

movable soldering implements in communication with said gas supply and means for moving said soldering implements to effect the soldering and release thereof and means operating upon the soldering implements to determine the length of time the implements shall be applied in finishing the soldering.

10. In a machine of the character described, a rotary pocketed wheel, a coöperating guide rail by contact with which the cans are revolved, a gas chamber and connections, steels mounted to be raised and lowered, and means for holding the steels in elevated position and means operating upon the soldering implements to determine the length of time the implements shall be applied in finishing the soldering.

11. In a machine of the character described, a rotary pocketed wheel, a coöperating guide rail by contact with which the cans are revolved, a gas chamber and connections, steels mounted to be raised and lowered, means for holding the steels in elevated position, and means permitting the steels to drop to solder the can and means operating upon the soldering implements to determine the length of time the implements shall be applied in finishing the soldering.

12. In a machine of the character described, a rotary pocketed wheel, a coöperating guide rail by contact with which the cans are revolved, a gas chamber and connections, steels mounted to be raised and lowered, means for holding the steels in elevated position, means permitting the steels to drop to solder the can, and means for regulating the time the steel shall be applied in finishing the soldering.

13. In a machine of the character described, a rotary pocketed wheel, a guide rail for coöperation therewith and by contact with which and said pockets the cans are revolved, means for adjusting the size of the pockets to the size of the cans, a gas chamber and supply pipes, steels mounted to be raised and lowered, a track having a depressed portion and means on the steels engageable therewith.

14. In a machine of the character described, a rotary pocketed wheel, a guide rail for coöperation therewith and by contact with which and said pockets the cans are revolved, means for adjusting the size of the pockets to the size of the cans, a gas chamber and supply pipes, steels mounted to be raised and lowered, a track having a depressed portion, means on the steels engageable therewith, and means to regulate the length of time the steel shall be applied in finishing the soldering.

15. In a machine of the character described, the combination with a can conveyer, a bed to receive the cans from said

conveyer, a rotary can carrier, a series of rotary soldering implements disposed above the center of the cans and a track upon which the said implements travel and are guided, said track having a raised portion to hold the implements in elevated position and a depressed portion to allow said implements to descend upon and seal the cans, and an adjustable connection between the raised

and depressed portions of the track for 10 regulating the time of the application of the soldering implements.

In testimony whereof I affix my signature in presence of two witnesses.

HAROLD E. SHAW.
